SHEET METAL PANEL

Norman Oliver and Richard Moyer, Sioux Falls, S. Dak.,
assignors to Sioux Steel Company, Sioux Falls, S. Dak.

Filed Apr. 27, 1964, Ser. No. 79,697

Term of patent 14 years

(Cl. D54—2)

FIG. 1.

FIG. 2.

FIGURE 1 is a front elevational view of the sheet metal panel.

FIGURE 2 is a bottom edge view, it being understood that the top edge view would be identical but in reverse.

FIGURE 3 is an enlarged end view of the sheet metal panel.

The panel is broken away at the center thereof in FIGURES 1 and 2 to indicate an article of indeterminate length.

We claim:

The ornamental design for a sheet metal panel, as shown and described.
